DISPLAY RACK

Martin P. Levin, Rye, N. Y., assignor to Grosset & Dunlap, Inc., New York, N. Y., a corporation of New York

Application November 2, 1950, Serial No. 12,820

Term of patent 7 years

(Cl. D80—9)

To all whom it may concern:

Be it known that I, Martin P. Levin, a citizen of the United States, residing in Rye, county of Westchester, State of New York, have invented a new, original, and ornamental Design for a Display Rack of which the following is a specification, reference being had to the accompanying drawings, forming a part hereof.

Figure 1 of the drawings is a view in perspective of a display rack showing my new design.

Figure 2 is a top plan view thereof.

Figure 3 is a side elevational view thereof.

Figures 2 and 3 are drawn to a smaller scale than Figure 1.

I claim:

The ornamental design for a display rack as shown and described.

MARTIN P. LEVIN.
